Primary Examiner — Bridget L Eland(74) *Attorney, Agent, or Firm* — Carr & Ferrell LLP(57) **CLAIM**

The ornamental design for a wireless repeater, as shown and described.

DESCRIPTION

FIG. 1 is a perspective view of a wireless repeater illustrating our new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The broken lines immediately adjacent the claimed areas represent the bounds of the claimed design while all other broken lines including the "m" are directed to environment and are for illustrative purposes only; the broken lines form no part of the claimed design.

The center "m" logo in FIGS. 1, 2, and 4-7 forming part of the disclosure is a registered trademark of Mimosa Networks, Inc.
